CLAIM

The ornamental design for an artificial tree, substantially as shown and described.

DESCRIPTION

FIG. 1 is a perspective view of an artificial tree showing my new design;

FIG. 2 is a front elevational view;

FIG. 3 is a top plan view; and

FIG. 4 is a bottom plan view.

The unseen surfaces of the spiralling band are the same as those shown, and the back and left side of the base are unornamented.

FIG. 1

FIG. 2

FIG. 3

FIG. 4
